Conrad Harris & Paul W. Zorner, of Cincinnati, Ohio, Assignors to Harris, Zorner & Co., of same place.
Letters Patent No 1076. Dated, Jan. 4-1859.

The Schedule referred to in these Letters Patent and making part of the same,

To all whom it may concern,

Be it known that we Conrad Harris and Paul W. Zorner, both of Cincinnati, County of Hamilton, State of Ohio, have invented or produced a new Original design for Coal Cooking Stoves, and we do hereby declare that the following is a full and exact description of the same, reference being had to the annexed drawings and to the letters of reference, marked thereon, to wit

Letter A, being, a perspective view of the stove.

Having thus described our joint invention, what we claim therein as new and desire to secure by Letters Patent, is

The scrolls foliage and moldings as set forth in the annexed drawings and thereby forming an ornamental design for Coal Cooking Stoves to be known and called the Pluto.

Mitnesed
